AIRPLANE

Albert J. Lechner, North Hollywood, Calif., assignor to
Lockheed Aircraft Corporation, Burbank, Calif.

Filed Dec. 5, 1960, Ser. No. 63,116

Term of patent 14 years

(Cl. D71—1)

Des. 195,067

PAGE 2

Fig. 3

FIGURE 1 is a side elevational view of an airplane embodying my new design;

FIGURE 2 is a front elevational view thereof; and FIGURE 3 is a top plan view thereof.

FIGURE 4 is a fragmentary perspective view of the front portion thereof.

FIGURE 5 is a bottom fragmentary perspective view thereof.

The dominant features of my design reside in those portions shown in full lines.

I claim:

The ornamental design for an airplane, substantially as shown and described.
